US008544230B2

(12) **United States Patent**
Pervan

(10) **Patent No.:** **US 8,544,230 B2**
(45) **Date of Patent:** **Oct. 1, 2013**

(54) **MECHANICAL LOCKING SYSTEM FOR FLOOR PANELS**

(75) Inventor: **Darko Pervan**, Viken (SE)

(73) Assignee: **Valinge Innovation AB**, Viken (SE)

(*) Notice: Subject to any disclaimer, the term of this patent is extended or adjusted under 35 U.S.C. 154(b) by 53 days.

(21) Appl. No.: **12/977,399**

(22) Filed: **Dec. 23, 2010**

(65) **Prior Publication Data**

US 2011/0167750 A1 Jul. 14, 2011

Related U.S. Application Data

(60) Provisional application No. 61/294,217, filed on Jan. 12, 2010.

(30) **Foreign Application Priority Data**

Jan. 12, 2010 (SE) 1050018-9

(51) **Int. Cl.**
E04B 2/00 (2006.01)

(52) **U.S. Cl.**

USPC **52/582.1**; 52/391; 52/588.1; 428/50

(58) **Field of Classification Search**

USPC 52/390, 392, 533, 534, 539, 553, 52/578, 582.1, 586.1, 586.2, 588.1, 589.1, 52/590.2, 590.3, 591.1, 591.2, 591.3, 591.4, 52/591.5, 592.1, 592.2, 592.4, 745.08, 745.19, 52/747.1, 747.11, 748.1, 748.11; 403/334, 403/345, 364-368, 372, 375, 376, 381; 404/34,

OTHER PUBLICATIONS

Pervan, Darko, et al., U.S. Appl. No. 13/670,039, entitled "Mechanical Locking of Floor Panels with a Flexible Tongue," filed in the U.S. Patent and Trademark Office on Nov. 6, 2012.

(Continued)

Primary Examiner — William Gilbert

(74) *Attorney, Agent, or Firm* — Buchanan Ingersoll & Rooney P.C.

(57) **ABSTRACT**

Floor panels (1b, 1c) provided with a mechanical locking system made of a separate material in order to reduce snapping resistance during vertical displacement.

16 Claims, 7 Drawing Sheets

MECHANICAL LOCKING SYSTEM FOR
FLOOR PANELSCROSS REFERENCE TO RELATED
APPLICATIONS

The present application claims the benefit of U.S. Provisional Application No. 61/294,217, filed on Jan. 12, 2010, and claims the benefit of Swedish Application No. 1050018-9, filed on Jan. 12, 2010. The entire contents of each of U.S. Provisional Application No. 61/294,217 and Swedish Application No. 1050018-9 are hereby incorporated herein by reference.

TECHNICAL FIELD

The invention generally relates to the field of mechanical locking systems for floor panels and building panels especially floor panels with mechanical locking systems, which are possible to lock with a vertical displacement.

FIELD OF APPLICATION OF THE INVENTION

Embodiments of the present invention are particularly suitable for use in floating floors, which are formed of floor panels which are joined mechanically with a locking system integrated with the floor panel, i.e. mounted at the factory, that are made up of one or more upper layers of veneer, decorative laminate or decorative plastic material, an intermediate core of wood fibre based material or plastic material and preferably a lower balancing layer on the rear side of the core. The following description of known technique, problems of known systems and objects and features of the invention will therefore, as a non restrictive example, be aimed at this field of application and in particular at paper based or paper free laminate flooring formed as rectangular floor panels with long and shorts sides intended to be mechanically joined on both long and short sides. The long and short sides are mainly used to simplify the description of the invention. The panels can be squared and can have more than four sides, which are not parallel or perpendicular to each other.

It should be emphasized that embodiments of the invention can be applied to any floor panel and it could be combined with all types of known locking system, where the floor panels are intended to be joined using a mechanical locking system connecting the panels in the horizontal and vertical directions on at least two adjacent sides. The invention can thus also be applicable to, for instance, solid wooden floors, parquet floors with a core of wood or wood fibre based material and a surface of wood or wood veneer and the like, floors with a printed and preferably also varnished surface, floors with a surface layer of plastic or cork, linoleum, rubber or similar. Even floors with hard surfaces such as stone, tile and similar are included and floorings with soft wear layer, for instance needle felt glued to a board. Embodiments of the invention can also be used for joining building panels which preferably contain a board material for instance wall panels, ceilings, furniture components and similar.

BACKGROUND OF THE INVENTION

Laminate flooring usually comprising a core of 6-12 mm fibreboard, a 0.2-0.8 mm thick upper decorative surface layer of laminate and a 0.1-0.6 mm thick lower balancing layer of laminate, plastic, paper or like material. A laminate surface comprising a melamine impregnated paper. Recently printed surfaces and wood fibre based paper free laminate surfaces

2

have been developed. The most common core material is a fibreboard with high density and good stability usually called HDF—High Density Fibreboard. Sometimes also MDF—Medium Density Fibreboard—is used as core.

5 Laminated floor panels are generally joined mechanically by means of so called mechanical locking systems. These systems comprise locking means, which lock the panels horizontally and vertically. The mechanical locking systems are usually formed by machining the core of the panel. Alternatively, parts of the locking system can be formed of separate materials, which are integrated with the floor panel, i.e. joined with the floor panel in connection with the manufacture thereof.

10 The main advantages of floating floors with mechanical locking systems are that they are easy to install. Preferably, they can also easily be taken up again and used once more at a different location.

Definition of Some Terms

15 In the following text, the visible surface of the installed floor panel is called “front side”, while the opposite side of the floor panel, facing the sub floor, is called “rear side”. The edge between the front and rear side is called “joint edge”. By 20 “horizontal plane (HP) or principal plane” is meant a plane, which extends parallel to the outer part of the surface layer. Immediately juxtaposed upper parts of two adjacent joint edges of two joined floor panels together define a “vertical plane (VP)” perpendicular to the horizontal plane. By “horizontally” is meant parallel to the horizontal plane and by 25 “vertically” parallel to the vertical plane. By “up or upwardly” is meant towards the front side and by “down or downwardly” is meant towards the rear side. By “inwardly” is 30 meant essentially horizontally towards the inner part of the panel and by “outwardly” is meant essentially horizontally and away from the inner part of the panel. By “strip panel” is 35 meant a panel comprising a strip and a locking element. By “groove panel” is meant a panel with a locking groove intended to cooperate with a locking element for horizontal 40 locking.

Known Technique and Problems Thereof

The description of the known art below is in applicable 45 parts also used in embodiments of the invention.

For mechanical joining of long sides as well as short sides in the vertical and horizontal direction several methods and locking systems could be used. One of the most used methods is the angle-snap method and one of the most used locking 50 systems is a system made in one piece with the core. The long sides are installed by angling. The panel is then displaced in locked position along the long side. The short sides are locked by horizontal snapping.

An alternative method is the so-called angling-angling 55 method whereby long and short sides are locked with angling.

Recently a new and simpler method has been developed where all floor panels can be joined with just an angling of the long edges. This installation method generally referred to as “fold down” installation method is described in FIGS. 1-4.

60 The locking of the short edges 1a, 1b takes place with a scissors like movement where a flexible tongue 31 is displaced inwardly gradually from one edge to the other edge when a long side of a panel 1c in one row is connected by angling to an adjacent panel 1a in a previously installed row. 65 The flexible snap tab, which in most cases is made of a plastic section, is during folding bended horizontally along the joint. A part of the snap tab is during folding almost in a locked

position, as shown in FIG. 1, and other parts are in contact with the adjacent edge, FIG. 2, or in an completely unlocked position, as shown in FIG. 4.

Some versions of flexible tongues which are generally made of an extruded plastic section have an inner part, which is connected in a holding groove 32 and an outer flexible snap tab pointing downwards 33 that during folding snaps into a tongue groove 31 of an adjacent panel 1c. The flexible tongue is generally connected to an edge of the strip panel. It could also be connected to the groove panel. The snap tab is in such a version extending upwards.

The main problem with know flexible tongue 30 as shown in FIG. 2 is that it is difficult to lock due to limited flexibility. The contact point P between the groove panel and the flexible snap tab 33 is at an upper part when the groove panel is folded down along the vertical plane VP. The snap tab is also rather rigid due to the fact that the vertical extension T1 is less than 0.3 times the floor thickness T. The snap tab is also pushed inwardly and intersects the vertical plane VP. The holding groove must be made rather large in order to provide stability and this is a disadvantage.

FIGS. 5a and 5b show a snap tab with improved flexibility. It has an inner part 30a and an outer part 30b that are flexible. The snap tab must be displaced in the holding groove during locking and this requires tight tolerances. The snap is displaced into the holding groove 32, which must have a considerable horizontally extending depth.

FIGS. 6a and 6b show a locking system on the market where the contact point P is on the upper part of the flexible snap tab, which is displaced inwardly beyond the vertical plane in order to improve flexibility. The groove must be rather deep and this effect the stability of the edge in a negative way.

FIGS. 6c and 6d show another locking system on the market, which is made of three parts, two rather rigid parts 30a, 30b and one flexible rubber like part 30c.

FIGS. 6e, 6f show a locking system with a simple cross section, which is schematically shown in WO 2007/079845, FIG. 22, where the flexible snap tab 33 is made of a narrow rectangular cross-section that is bent or curved shaped. The snap tab is bended outside the vertical plane. The disadvantage is that the vertical extension of the holding groove is very small and difficult to produce with rotating tools. The flexible tongue 30 is difficult to fix into the groove and has a limited flexibility. The main disadvantage is however that the snap tab is bent around a centre point CP that is in contact with the lower part of the groove 32. This will in most cases cause a breaker or a permanent bending in many materials especially an extruded plastic material. The embodiment combines three major disadvantages: a) a deep holding groove, b) limited flexibility of the snap tab and c) high snapping resistance.

All the shown known embodiments have snap tabs, which have a vertical extension T1 that is smaller than 0.3 times the floor thickness T, and this creates a considerable snapping resistance during folding especially if it is combined with contacts points P at the upper part of the snap tab.

The function of a locking system with a snap tab could be improved if flexibility of the snap tab could be increased and if the horizontal extension of the holding groove could be reduced.

BRIEF DESCRIPTION OF THE INVENTION AND OBJECTS THEREOF

An objective of certain embodiments of the present invention is to provide an improved mechanical locking system

comprising a flexible tongue with an outer flexible snap tab, which could be locked by vertical folding.

More specifically the object is to provide a vertical snap locking system, which creates less snapping resistance and which has a more stable edge than the known systems.

The objective is to improve the stability of the edge mainly with holding grooves that allow a strong connection between a flexible tongue and the holding groove and that have a smaller horizontal extension inwardly into the core of the panel than present known systems.

The above objects of certain embodiments of the invention are achieved wholly or partly by a mechanical locking systems and floor panels, as described herein. Further embodiments of the invention are evident from the claims, description and drawings.

According to a first aspect of certain embodiments of the invention, a set of floor panels are provided which are mechanically connectable to each other along one pair of adjacent edges, so that upper joint edges of said floor panels in the connected state define a vertical plane. Each of said floor panels comprising a flexible tongue on a first edge of the panel and a tongue groove on a second opposite edge of the panel for receiving the flexible tongue of an adjacent panel for mechanically locking together said adjacent edges vertically parallel to the vertical plane and at right angles to a horizontal plane of the panels.

The tongue groove is formed in a core of the panel and is open towards the vertical plane. A locking element is formed in one piece with the panel at the first edge and a locking groove at the opposite second edge. The locking groove being open towards a rear side of the panel that faces a subfloor.

The locking element and the locking groove form a horizontal mechanical connection perpendicular to the vertical plane, the locking element having a locking surface that is adapted to directly contact a locking surface of the locking groove for locking the panels to each other horizontally parallel to the horizontal plane and at right angles to the joined first and second edges.

The flexible tongue comprises resilient parts formed of a separate material than the core, and cooperates with a locking surface in the tongue groove.

Wherein two of the panels can be mechanically joined together by displacement of said two panels vertically towards each other, while at least an outer part of the flexible tongue, comprising a flexible snap tab extending downwards is resiliently displaced inwardly, substantially around a centre point located at an upper part of the flexible tongue and spaced from the lower part of the holding groove, to an inner position which is outside the vertical plane, until said adjacent edges of the two panels are brought into engagement with each other vertically and the flexible snap tab is displaced towards its initial position away from the vertical plane and against the tongue groove.

The flexible tongue has an inner part mounted in a sideward open holding groove in the first edge that is open towards the vertical plane. The inner part is fixed in the sideward open holding groove.

The outer flexible part, e.g., the flexible snap tab, has a cross section with a maximum thickness of the outer flexible part (e.g., the flexible snap tab), and the locking surface being offset in relation to the vertical plane by at least the maximum thickness of the flexible snap tab.

According to a second aspect of certain embodiments of the invention, a set of floor panels are provided which are mechanically connectable to each other along one pair of adjacent edges, so that upper joint edges of said floor panels in the connected state define a vertical plane. Each of said

floor panels comprising a flexible tongue on a first edge of the panel and a tongue groove on a second opposite edge of the panel for receiving the flexible tongue of an adjacent panel for mechanically locking together said adjacent edges vertically parallel to the vertical plane and at right angles to a horizontal plane of the panels.

The tongue groove is formed in a core of the panel and is open towards the vertical plane. A locking element is formed in one piece with the panel at the first edge and a locking groove at the opposite second edge. The locking groove being open towards a rear side of the panel that faces a subfloor.

The locking element and the locking groove form a horizontal mechanical connection perpendicular to the vertical plane, the locking element having a locking surface that is adapted to directly contact a locking surface of the locking groove for locking the panels to each other horizontally parallel to the horizontal plane and at right angles to the joined first and second edges.

The flexible tongue comprises resilient parts formed of a separate material than the core, and cooperates with a locking surface in the tongue groove.

Wherein two of the panels can be mechanically joined together by displacement of said two panels vertically towards each other, while at least an outer part of the flexible tongue, comprising a flexible snap tab extending downwards is resiliently displaced inwardly until said adjacent edges of the two panels are brought into engagement with each other vertically and the flexible snap tab is displaced towards its initial position away from the vertical plane and against the tongue groove.

The flexible tongue has an inner part mounted in a sideward open holding groove in the first edge that is open towards the vertical plane. The inner part is fixed in the sideward open holding groove.

The outer flexible part, e.g., the flexible snap tab, has a cross section with a maximum thickness of the outer flexible part (e.g., the flexible snap tab), and the locking surface being offset in relation to the vertical plane by at least the maximum thickness of the flexible snap tab.

The inner part comprises one or several vertical cross sections wherein one of said vertical cross sections may be larger than said thickness of the flexible snap tab and/or another vertical cross section of the inner part.

BRIEF DESCRIPTION OF THE DRAWINGS

FIGS. 1-6 illustrate known systems.

FIGS. 7a-c illustrate a first embodiment of the invention.

FIGS. 8a-d illustrate a second embodiment of the invention.

FIGS. 9a-c illustrate a third embodiment of the invention.

FIGS. 10a-c illustrate a flexible tongue fixed to an edge of the fold panel.

FIG. 10d illustrates a flexible tongue fixed in an inclined groove.

DESCRIPTION OF EMBODIMENTS OF THE INVENTION

To facilitate understanding, several locking systems in the figures are shown schematically. It should be emphasized that improved or different functions can be achieved using combinations of the preferred embodiments.

FIGS. 7a-7c show an embodiment of the invention. A strip panel 1b comprising a strip 6 and a locking element 8 which cooperates with a locking groove 14 in a groove panel 1c for horizontal locking of two adjacent edges of panels 1b, 1c is

provided. The strip panel comprises a flexible tongue 30 in a holding groove 32, which is open towards the vertical plane VP and has an inner part IP connected to the holding groove. The flexible tongue has an outer part OP outside the vertical plane VP comprising a flexible snap tab 33 that cooperates with a locking surface 40 of a tongue groove 31 in an adjacent edge 1c of the groove panel 1c and locks the edges vertically parallel to the vertical plane VP.

The snap tab is during the whole locking motion positioned outside the vertical plane VP and is during locking displaced inwardly towards the vertical plane and outwardly away from the vertical plane as shown in FIGS. 7b and 7c. The snap tab is during the displacement bended around a centre point which is located at an upper part of the flexible tongue 30 and is preferably spaced vertically upwards from the lower part of the holding groove 32 and/or horizontally outwardly from the vertical plane VP. The snap tab is preferably spaced from the vertical plane in its inner position. The inner part of the snap tab could also preferably be aligned with the vertical plane.

Such an embodiment makes it possible to decrease the amount of material that has to be removed in order to form a holding groove. The horizontal extension of the holding groove 32 could be decreased and even the opening could be smaller. This improves the stability of the edge. The improved stability could be combined with a maintained or even improved flexibility of the snap tab.

The groove panel 1c comprises a lower part 36, which is preferably formed as a bevel, and preferably more vertically inclined than the outer part 37 of the flexible snap tab. The first contact point P between the groove panel 1c and the flexible tongue 30 is preferably located at the lower part of the flexible snap tab 33 when the groove panel 1c is displaced vertically along the vertical plane VP towards the strip panel 1b. Such an embodiment will decrease the snapping resistance considerably.

The lower part of the holding groove 32 is preferably located in a horizontal plane H1 which is vertically offset upwardly from a vertical plane H3 that intersects the upper part of the strip 6 and preferably also from a horizontal plane H2 that intersects the upper part of the locking element. This facilitates the fixing of the tongue into the holding groove. The holding groove could also be inclined upwardly from an inner to an outer position. This is an advantage, which could be used in all snap tab systems, such as the known art systems previously discussed, to facilitate the fixing of the flexible tongue. Embodiments of the known art systems previously discussed with an inclined holding groove are included within the scope of the invention.

The flexible tongue has preferably a thickness A-A at its outer part OP that is smaller than a vertical thickness B-B located in the inner part IP. The inner part IP of the flexible tongue 30 comprises preferably two vertical cross sections B-B, B'-B', with different vertical thicknesses and preferably a space 39 between a lower and/or upper part of the flexible groove. Such an embodiment makes it possible to combine a stable connection of the flexible tongue, to save material and to improve flexibility.

The locking surface 40 is offset to the vertical plane by at least the maximum thickness A-A of the flexible snap tab 33.

The inner part of the flexible tongue 30 can substantially fill the volume of the sideward open holding groove or can comprise one or several friction connection 38 that extends downwards and/or upwards.

The described motion of a flexible snap tab outside the vertical plane and a first contact point at a lower part of the snap tab could be used separately to improve locking but preferably in combination. It is an advantage to use a low

contact point even in embodiments where the snap tab is displaced inwardly beyond the vertical plane.

FIGS. 8a-8c show that the snap tab 33 could preferably be formed with a vertical extension T1 that is equal or larger than 0.3 times the floor thickness T. It is even more preferred to increase this vertical extension to 0.35 or even to more than 0.40 times the floor thickness T. This is especially preferable in wood floors where a high locking strength could be combined with an easy locking.

Such an embodiment could be used to decrease the locking resistance further especially if it is combined with one or both of the two other desired features described above.

FIG. 8d shows an embodiment where the upper part 34 of the flexible tongue 30 can be bended horizontally inwardly, preferably to a position inside the vertical plane VP. When the upper part of the snap tab is in locked position, a space 35 exists between the flexible tongue and the holding groove 32. The upper part of the flexible tongue is displaced in the space 35 during locking. This can be used to reduce snapping resistance and to increase the flexibility of the flexible tongue.

FIGS. 9a-9c show a preferred embodiment of a flexible tongue 30, which is connected in a fixed manner in a holding groove 32 of the strip panel 1b and comprises a flexible part 33 that is displaceable in a displacement groove 32a. Such an embodiment allows increased flexibility since the vertical distance between the lower part of the tongue that is connected in the holding groove 32 and the upper part 33 that locks against the locking surface 40 of the tongue groove 31, could be increased.

The flexible snap tab 33 is during folding displaced horizontally inwards and outwards in the displacement groove 32a and bending occurs preferably and essentially around a centre point C located in a lower part of the flexible tongue 30.

The holding groove 32 is located vertically below the displacement groove 32a. The locking surface 40 of the tongue groove 31 is preferably spaced vertically upwards in relation to the holding groove 32 and these two grooves are preferably located in different horizontal planes one over the other. The holding groove 32 is preferably located vertically below the upper part of the locking element 8 and is preferably inclined upwards in relation to a horizontal plane in order to facilitate the insertion of the flexible tongue 31 into the holding groove 32.

Such a flexible tongue could also be connected to an edge of the groove panel 1c. The holding groove 32 is in such an embodiment preferably located in the upper part of the panel edge and the displacement groove 32a below the holding groove 32.

FIGS. 10a-10c show that a flexible tongue could be connected to a holding groove 32 in the groove panel 1c and that the holding groove 32 is spaced inwardly from the locking groove 14. The holding groove 32 could even in this embodiment preferably be inclined against the horizontal plane.

FIGS. 10b and 10c show that the flexible snap tab 33 during locking slides against the upper and outer part 8a of the locking element 8. This part 8a is in this embodiment inclined. It could for example also be rounded. The outer part 33 of the snap tab locks against a locking surface 6a formed on the outer part of the strip 6. This locking surface 6a could be inclined downwards or upward, essentially horizontal or rounded.

FIG. 10d shows that all embodiments shown in FIGS. 7 and 8 could be connected to a holding groove 32 that is inclined in order to facilitate the fixing of the flexible tongue 30 when a holding groove 32 is formed in the strip panel 1b.

The invention claimed is:

1. A set of floor panels which are mechanically connectable to each other along one pair of adjacent edges, so that upper joint edges of said floor panels in the connected state define a vertical plane, each of said floor panels comprising:

a flexible tongue on a first edge of the panel;

a tongue groove on a second opposite edge of the panel for receiving the flexible tongue of an adjacent panel for mechanically locking together said adjacent edges vertically parallel to the vertical plane and at right angles to a horizontal plane of the panels;

the tongue groove is formed in a core of the panel and is open towards the vertical plane;

10 a locking element formed in one piece with the panel at the first edge and a locking groove at the opposite second edge, the locking groove being open towards a rear side of the panel that faces a subfloor;

15 the locking element and the locking groove form a horizontal mechanical connection perpendicular to the vertical plane, the locking element having a locking surface that is adapted to directly contact a locking surface of the locking groove for locking the panels to each other horizontally parallel to the horizontal plane and at right angles to the joined first and second edges;

the flexible tongue comprising resilient parts formed of a separate material than the core, and cooperates with a locking surface in the tongue groove;

20 wherein two of the panels can be mechanically joined together by displacement of said two panels vertically towards each other, while at least an outer part of the flexible tongue, comprising a flexible snap tab extending downwards, is resiliently displaced inwardly, substantially around a centre point located at an upper part of the flexible tongue and spaced from the lower part of a sideward open holding groove in which at least a part of the flexible tongue is mounted, to an inner position which is outside the vertical plane until said adjacent edges of the two panels are brought into engagement with each other vertically and the flexible snap tab is displaced towards its initial position away from the vertical plane and against the tongue groove, and

25 wherein the flexible tongue has an inner part mounted in the sideward open holding groove in the first edge that is open towards the vertical plane, the inner part is fixed in the sideward open holding groove,

30 wherein the flexible snap tab has a cross section with a maximum thickness, and an edge of the locking surface closest to the vertical plane being offset in relation to the vertical plane by at least the maximum thickness of the flexible snap tab.

35 2. The set of floor panels as claimed in claim 1, wherein the inner part comprises one or several vertical cross sections and wherein at least one of said vertical cross sections is larger than said thickness of the flexible snap tab and/or another vertical cross section of the inner part.

40 3. The set of floor panels as claimed in claim 1, wherein the flexible snap tab during locking is bent horizontally along the joint edge.

45 4. The set of floor panels as claimed in claim 1, wherein a lower part of the second edge and the flexible snap tab are configured such that the first contact point between the second edge and the flexible snap tab is located at the lower part of said flexible snap tab when the second edge is displaced along the vertical plane towards the first edge.

50 5. The set of floor panels as claimed in claim 1, wherein the vertical extension of the flexible snap tab is equal or larger than 0.3 times the floor panel thickness.

6. The set of floor panels as claimed in claim 1, wherein the flexible tongue is made of extruded polymer material.
7. The set of floor panels as claimed in claim 1, wherein the second edge comprises a lower part formed as a bevel.
8. The set of floor panels as claimed in claim 7, wherein the lower part is more vertically inclined than an initial position of the flexible snap tab.
9. The set of floor panels as claimed in claim 1, wherein there is a space between an upper part of the flexible tongue and the holding groove and wherein the upper part of the flexible tongue is displaced in said space during locking. 10
10. The set of floor panels as claimed in claim 1, wherein the centre point of the flexible tongue is outside the vertical plane.
11. The set of floor panels as claimed in claim 1, wherein the entire flexible snap tab is outside the vertical in its initial position after the two floor panels are connected. 15
12. A set of floor panels which are mechanically connectable to each other along one pair of adjacent edges, so that upper joint edges of said floor panels in the connected state define a vertical plane, each of said floor panels comprising: 20
a flexible tongue on a first edge of the panel;
a tongue groove on a second opposite edge of the panel for receiving the flexible tongue of an adjacent panel for mechanically locking together said adjacent edges vertically parallel to the vertical plane and at right angles to a horizontal plane of the panels; 25
the tongue groove is formed in a core of the panel and is open towards the vertical plane;
a locking element formed in one piece with the panel at the first edge and a locking groove at the opposite second edge, the locking groove being open towards a rear side of the panel that faces a subfloor;
the locking element and the locking groove form a horizontal mechanical connection perpendicular to the vertical plane, the locking element having a locking surface that is adapted to directly contact a locking surface of the locking groove for locking the panels to each other horizontally parallel to the horizontal plane and at right angles to the joined first and second edges; 30
the flexible tongue comprising resilient parts formed of a separate material than the core, and cooperates with a locking surface in the tongue groove; 35

wherein two of the panels can be mechanically joined together by displacement of said two panels vertically towards each other, while at least an outer part of the flexible tongue, comprising a flexible snap tab extending downwards, is resiliently displaced inwardly to an inner position which is outside the vertical plane until said adjacent edges of the two panels are brought into engagement with each other vertically and the flexible snap tab is displaced towards its initial position away from the vertical plane and against the tongue groove, and

wherein the flexible tongue has an inner part mounted in a sideward open holding groove in the first edge that is open towards the vertical plane, the inner part is fixed in the sideward open holding groove,

wherein the flexible snap tab has a cross section with a maximum thickness, and an edge of the locking surface closest to the vertical plane being offset in relation to the vertical plane by at least the maximum thickness of the flexible snap tab and,

wherein the inner part comprises one or several vertical cross sections and wherein at least one of said vertical cross sections is larger than said thickness of the flexible snap tab and/or another vertical cross section in the inner part.

13. The set of floor panels as claimed in claim 12, wherein the flexible snap tab is resiliently displaced inwardly substantially around a centre point located at an upper part of the flexible tongue and spaced from the lower part of the holding groove.

14. The set of floor panels as claimed in claim 13, wherein there is a space between the inner part of the flexible tongue and the lower part of the holding groove. 35

15. The set of floor panels as claimed in claim 13, wherein the centre point of the flexible tongue is outside the vertical plane.

16. The set of floor panels as claimed in claim 12, wherein the entire flexible snap tab is outside the vertical in its initial position after the two floor panels are connected. 40
